UNITED STATES PATENT OFFICE.

JOHN S. RAPSON, OF JENKINTOWN, PENNSYLVANIA.

ERASIVE TABLET.

No. 923,576.

Specification of Letters Patent.

Patented June 1, 1909.

Application filed December 14, 1908. Serial No. 467,507.

To all whom it may concern:

Be it known that I, JOHN S. RAPSON, a citizen of the United States, and a resident of Jenkintown, county of Montgomery, 5 State of Pennsylvania, have invented an Improvement in Erasive Tablets, of which the following is a specification.

My invention has reference to erasive tablets and consists of certain improvements which are fully set forth in the following specification, and shown in the accompanying drawings which form a part thereof.

Heretofore it has been customary to form erasers hard for pencil or ink in solid tablets 15 and in some cases where the eraser is to be more yielding as for purposes of cleaning drawings where great abrasive action is not required, the end of the rubber tablet has been sub-divided in the direction of the 20 length of the tablet so as to present a large number of independent filaments which are perfectly flexible when the rubber is used upon the paper.

The object of my invention is to provide 25 an erasive tablet hard for pencil or ink in which there is provided a series of detachable portions, said portions being connected at their ends into an integral structure with the body of the tablet. When the outer- 30 most portion is soiled or materially reduced in effectiveness by wear and contact with objectionable matter, it may be detached and thereby leave a new and fresh portion 35 of the eraser properly shaped for immediate use and in a perfectly clean and unused condition.

My invention consists of an erasive tablet 40 formed of elastic erasive material and having a portion thereof provided with transverse incisions either wholly or part way through the body to form bars or layers which are connected at their ends with the body so as to maintain a definite position in use and to prevent the separation of the said layers except when intentionally done for the purpose 45 of bringing the new layer into operative position upon the tablet.

My invention also comprehends details of 50 construction which together with the features above specified, will be better understood by reference to the drawings in which—

Figure 1 is a plan view of an eraser tablet 55 embodying my invention; Fig. 2 is a sectional elevation of the same on line 2—2; Fig. 3 is a view similar to Fig. 1 showing the

slits or incisions in curved form, and Fig. 4 is a sectional elevation corresponding to Fig. 2 showing the modification of my invention.

60

A is the body of the tablet and may be all of soft rubber such as required for the erasure of pencil marks or may be partly made of abrading rubber compound such as commonly known as ink erasers and which is

65 indicated at F in Fig. 1. I prefer to form the end of the erasive tablet A V shaped, as indicated at B, and parallel to the outer V shaped walls I provide a series of parallel incisions or slits C which form a correspond- 70

ing series of bars S of erasive material, said bars being united at their ends by continuous portions D and E and integral with the 75 ends of said bars and with the body of the tablet A, as will be clearly understood by reference to Fig. 1. As shown, there are two sets of the incisions, the incisions of one set being arranged obliquely to the incisions of the other set so that as the outermost bars

are used and removed the successive bars 80 will occupy substantially the same position with reference to the body of the eraser, that was occupied by the outermost bars. In ordinary use the outermost bar on one side and the outermost bar on the other side 85

would be indiscriminately used so that they might both be removed at or about the same time to bring fresh bars into operative position. The removal of the outermost bars may 90 be accomplished either by simply tearing them off or more preferably by severing the connecting parts D and E in line with the incisions

95 by use of a knife, as will be readily understood. The incisions C may extend entirely through the body of the tablet A as indicated in Fig. 2, or if desired these incisions may extend only part way through from either or both sides so as to form a very thin connecting layer G, which will unite with the parts D and E, said construction being indicated in 100

Fig. 4. In this manner somewhat more stability will be given to the bars S during their use in erasing and because of which it would be possible to make the bars S longer than would otherwise be the case.

105

In Fig. 3 I have shown the end of the erasive tablet as having curved edges and curved slits or incisions, but otherwise this structure is the same as in Fig. 1. It is evident that these incisions and connecting bars S so formed may be employed at any place upon the erasive tablet if so desired,

110

but I have shown them arranged at one end only as an example of a practical and satisfactory arrangement of said bars upon the tablet; I however do not restrict or confine myself in any manner as to the position or arrangement of said bars except that they shall be connected at their ends parallel or concentric according to the shape of the incisions. While I prefer the construction shown, the tablet may be modified without departing from the spirit of the invention. Having now described my invention what I claim as new and desire to secure by Letters Patent, is:

15 1. An erasive tablet consisting of a flat body of erasive material having a plurality of incisions terminating at each end within the erasive material and forming a plurality of parallel bars integrally connected together at their ends and to the body of the tablet.

20 2. An erasive tablet consisting of a flat body of erasive material having a plurality of incisions terminating at each end within the erasive material and forming a plurality of parallel bars integrally connected together at their ends and to the body of the tablet by a plurality of connecting bars arranged transversely to the parallel bars.

25 3. An erasive tablet consisting of a flat body of erasive material having a plurality of incisions extending entirely through the body and terminating at each end within the erasive material and forming a plurality of parallel bars of the thickness of the body integrally connected together at their ends and to the body of the tablet.

30 4. An erasive tablet consisting of a flat tablet of erasive material having one end

thereof V shaped and provided with two series of erasing bars arranged at an angle to each other and united by a transverse bar forming a part of the body of the tablet.

5. An erasive tablet consisting of a flat tablet of erasive material having one end thereof V-shaped and provided with two series of erasing bars arranged at an angle to each other and united by a transverse bar forming a part of the body of the tablet and in which the other or distant ends of the two series of bars are respectively connected integrally with other bars forming a part of the body of the tablet, whereby the bars of the two series are held to the body at each end.

6. An erasive tablet having a plurality of superimposed bars connected at their ends with the body of the tablet whereby they are held against displacement during use but may be easily detached to expose a fresh erasing surface.

7. An erasive tablet having its edge provided with an erasing bar integral at its ends with the body of the tablet.

8. An eraser consisting of a plurality of erasing bars arranged side by side and integrally connected at a plurality of distantly located places, whereby the bars are normally supported and held in proper relative positions and the outer bar may be easily detached to expose a fresh erasing surface.

In testimony of which invention, I hereunto set my hand.

JOHN S. RAPSON.
